UNITED STATES PATENT OFFICE.

WILLIAM J. GOSLING, OF MONTREAL, QUEBEC, CANADA, ASSIGNOR TO JAMES CORPORATION LIMITED, OF MONTREAL, CANADA.

RAZOR-BLADE STROPPER.

Application filed November 16, 1923. Serial No. 675,238.

This invention relates to new and useful improvements in stropping devices for safety razor blades and particularly blades of the double-edged type in which either 5 edge may be used for shaving.

The object of the invention is to provide a stropping device which will require no adjustment and which will automatically sharpen both edges of the blade evenly.

Another object is to provide a stropper for safety razor blades which will have no obstructions or parts protruding beyond the sides of the frame.

A further object is to provide a stropper 15 for safety razor blades which will hold the blade in one position with regard to its centre without the use of protruding locking mechanism.

A still further object is to provide a razor stropper of simple, strong and durable construction which will be inexpensive and which will be simple to manufacture.

In my invention, I provide a one-piece frame within which is mounted a blade 25 holder of two-part construction, one part being pivotally mounted in the frame and having embossed centering devices adapted to engage with the usual holes formed in the standard types of razor blades. The other 30 part of the holder is hinged in such a manner as to allow full opening of the hinged portion without fouling or interfering with any part of the frame. Rollers mounted on pins are provided between the frames to act 35 as an easy positioning medium for the strop. To one of the rollers is securely attached an arm, having a slot cut therein adapted to engage with a protruding lug formed in the oscillatably mounted portion of the holder.

40 The blades is locked in position by means of a sliding stud mounted on one of the embossed centering devices.

In the drawings which illustrate the invention;—

45 Fig. 1 is a side elevation of the stropping device.

Fig. 2 is an end view of Figure 1.

Fig. 3 is a sectional plan of the device taken on the line 3—3, Figure 1, showing the 50 blade holder in cross section.

Fig. 4 is a sectional plan of the frame taken on the line 4—4, Figure 1.

Fig. 5 is a sectional view of the frame taken on the line 5—5, Figure 4.

Fig. 6 is a plan view of the strip out of 55 which the frame is made.

Referring more particularly to the drawings, 11 designates a one-piece frame comprising two parallel sides 12 and 13 connected by means of a U-shaped portion 14 of 60 hollow circular cross section, shown in Figure 5, and formed by rolling part of the frame 11 at the centre during the process of manufacture. The frame is formed from a strip of metal 15 shown in Figure 6, the 65 part used for the frame being shown in chain dotted lines and designated 16^a. The frame, being of one-piece construction, ensures a strong, durable device which will retain its shape, there being no part to work 70 loose. To hold the sides in parallel relation, a rivet 16 is passed through the frame at the upper edges and two rivets 17 are passed through the frame at the lower edge, one on each side of the centre line. Mounted on 75 rivets are the rollers 18, which are adapted to guide and assist in the free movement of the flexible leather or composite strop 19, which is placed around the top of the upper roller and in contact with the inner surface 80 of the lower rollers, that is, the surface facing the centre of the frame. Oscillatably mounted in the frame is the razor holder which is in two parts, one part 20 being provided with projecting pivots 21, which rotate 85 in bearings 22^a formed in the parallel members of the frame and to one side of the centre thereof. The part 20 is also provided with embossed circular portions 22 projecting outwardly from one face of the holder, 90 said projections being positioned so that they will engage with the holes 23 formed in the blade 24, which is of standard construction and provided with cutting edges 25 and 26.

To prevent the blade becoming detached 95 from the bosses, the hinged portion 27 of the holder is adapted to be held in position against the blade by means of the sliding locking member 28, which is mounted on one of the embossed circular projections 22, a 100 slot 29 being provided therein to allow free movement for the locking member. The hinged portion 27 is attached to the part 20 at one side thereof, the hinge 30 being so formed that the attaching portions or lugs 32 pass through slots 33 cut in the edge of the part 20. The lugs or attaching portions 105 are turned from the inner face 34 of the

hinged portion around the outer closing portion of the slots. This construction allows the hinged portion to be raised to a position at right angles to the portion 20 without fouling or interfering with the frame. It also allows the length of the blade holder to be made equal to the maximum distance between the parallel portions 12 and 13 of the frame. The edges 35 of the holder members are curved towards the centre of the holder, so that they will not foul the strop during the operation of sharpening the razor blade. The width of the holder and the hinged member is slightly less than the width of the blade, so that the edge of the blade will project slightly beyond the edge of the holder. Fixedly mounted on the upper roller in any suitable manner is the holder operating arm 36, which is provided with a slot 37 adapted to engage with a projecting lug 38 formed integral with the portion 20 of the holder. The length of the slot is made such that it will limit the movement of the holder in both directions of rotation. The position of the bearings in the parallel members is such that no part of the portion 20 of the holder needs to be offset to allow the edges of the blade to have even contact with the strop. The centre of the bearings is positioned from the centre of the frame an amount equal to half the thickness of the blade plus half the thickness of the portion 20 of the holder. This offsetting of the bearings allows the blade to oscillate as if it were pivoted about its own centre. Slight modifications may be made in the various parts of the device without departing from the spirit of the invention.

The operation of the device is as follows:—

The hinged portion of the blade holder is turned at right angles to the portion 20 and a blade is placed in position on the embossed projections which extend through the blade holes. The hinged portion is then turned into engaging position with the face of the blade, holes 39 being provided in the hinged portion to allow the embossed projections to pass therethrough. The blade is then locked in position between the hinged portion and the portion 20 by the sliding catch member

mounted on one of the embossed portions. A thin flexible strop of leather or like material is mounted on the upper roller and threaded through between the bottom rollers, said strop being so positioned that its inner faces are equidistant from a centre line passing through the centre of the frame. Attached to the upper roller is the operating arm having a slot, the edges of which are adapted to engage with a lug attached to the blade holder. The slot is of such length that it will limit the movement of the blade during the process of stropping. By pulling the strop first in one direction and then in the other, the blade holder oscillates on its supporting bearings in the frame through the action of the operating arm. The blade is adapted to project beyond the edges of the holder and comes in contact with the inner surface of the strop at two points, thus sharpening both edges on opposite sides of the blade in one operation. By reversing the action of the strop, the unstropped edges come in contact with the strop, thereby sharpening the blade evenly. The holder is so positioned that the blade oscillates about its centre, thus ensuring an even stropping action.

Having thus described my invention, what I claim is:—

A holder for safety razor blades comprising a pair of plates having corresponding ends hingedly connected together, a hollow boss projecting from the inner face of one plate and adapted to protrude through an opening formed in the other plate, said boss having a slot formed in the outer end thereof, a member passing through said slot and movable therein longitudinally of said plates, and heads at the opposite ends of said member adapted in one position of the member to be positioned within the circumferential boundary of the boss, and in another position of the member to be projected laterally beyond the boss so as to overlie the outer surfaces of the plates at one side of the boss to thereby secure the plates against separation.

In witness whereof, I have hereunto set my hand.

WILLIAM J. GOSLING.
